To all whom it may concern:

Be it known that I, Ernst A. Spuehler, a citizen of the United States of America and a resident of Elgin, in the county of Kane, State of Illinois, have invented a new, original, and ornamental Design for a Bottle, of which the following is a specification, reference being had to the accompanying drawing, forming a part thereof.

Figures 1, 2 and 3 are front, rear and side elevational views, respectively, of a bottle embodying my new design; and

Figure 4 is a perspective view of the top of the bottle on a larger scale.

I claim:

The ornamental design for a bottle, as shown.

ERNST A. SPUEHLER.
